PRETZEL BAKING OVEN

Charles W. King, 4418 Spruce St., Philadelphia, Pa.

Filed May 28, 1965, Ser. No. 85,488

Term of patent 14 years

(Cl. D81—10)

Fig. 1.

Fig. 4.

Fig. 5.

Fig. 5

Fig. 2

I claim:
The ornamental design for a pretzel baking oven, as shown.
